(57) **CLAIM**

The ornamental design for a pair of earphones and casing, as shown and described.

DESCRIPTION

FIG. 1 is a front, top, and right side perspective view of an earphone of a pair of earphones and casing showing our new design, the earphone is shown separately for purposes of illustration;

FIG. 2 is a bottom view thereof;

FIG. 3 is a left side view thereof;

FIG. 4 is a front view thereof;

FIG. 5 is a right side view thereof;

FIG. 6 is a top view thereof;

FIG. 7 is a rear view thereof;

FIG. 8 is a front, top, and right side perspective view of a pair of earphones and casing showing our new design, with the casing in an opened condition and holding two earphones;

FIG. 9 is a rear view thereof;

FIG. 10 is a right side view thereof;

FIG. 11 is a bottom view thereof;

FIG. 12 is a front view thereof;

FIG. 13 is a top view thereof;

FIG. 14 is a left side view thereof;

FIG. 15 is a front, top, and right side perspective view of a casing for a pair of earphones and casing showing our new design, with the casing in a closed condition, the casing is shown separately for purposes of illustration;

FIG. 16 is a top view thereof;

FIG. 17 is a front view thereof;

FIG. 18 is a right side view thereof, the left side view being a mirror image thereof;

FIG. 19 is a rear, bottom, and right side perspective view thereof; and,

FIG. 20 is a bottom view thereof.
